THREAD CONTROLLING DEVICE FOR CROSS THREAD LAYING MECHANISMS

James E. Moffatt, Chicago, Ill., assignor to Union Special Machine Company, Chicago, Ill., a corporation of Illinois

Original application July 19, 1928, Serial No. 294,009. Divided and this application May 15, 1930. Serial No. 452,683

9 Claims. (Cl. 112—245)

The invention relates to new and useful improvements in thread controlling devices for a stitching thread. The invention is particularly adapted for use with a cross thread laying mechanism such as described in my prior application, Serial Number 294,009, filed July 19, 1928, of which this application is a division.

An object of the present invention is to provide a thread controlling mechanism wherein a reciprocating member cooperating with thread guides carries independent devices operating in succession to take up and give up thread for each reciprocation of said member.

A further object of the invention is to provide a thread controlling mechanism which when operated in connection with a cross thread laying mechanism takes up the slack in the cross thread and places the cross thread under tension as the cross thread loop is completed so as to insure the proper positioning of the cross thread for the needles to pass the same.

A still further object of the invention is to provide a thread controlling mechanism which when operated with a cross thread laying mechanism takes up said cross thread after the completion of the cross thread loop for drawing the cross thread taut with the final stitch formation.

These and other objects will in part be obvious and will in part be hereinafter more fully disclosed.

In the drawings which show by way of illustration one embodiment of the invention:—

Fig. 1 is a front view of a part of a machine embodying the improvements.

Fig. 2 is a rear view of a portion of the machine.

Fig. 3 is an end view of a portion of the machine.

Fig. 4 is a view partly in section and partly in plan showing the cross thread guide, the devices for forming a loop in the cross thread, and means for supporting and actuating the same with the parts in position for completing the cross thread loop.

Fig. 5 is a similar view but showing the parts positioned for the loop forming device to engage the cross thread.

Fig. 6 is a front view showing more or less diagrammatically the needles, the cross thread guide, and the hook end of the loop forming device, and showing the position of the strand of the cross thread loop running to the cross thread guide.

Fig. 7 is an enlarged diagrammatic view show-

ing the needle threads and the cross thread formed into loops and locked thereby.

Fig. 8 is a view showing the thread controlling means for the cross thread in side elevation with the needle bar at the upper end of its stroke.

Fig. 9 is a similar view but showing in full lines the needle bar at the lower end of its stroke and in broken lines the cross thread controlling element as having completed its take-up action on the up-stroke of the needle bar.

Fig. 10 is a detail in plan showing the cross thread controlling means.

The invention is directed to devices for controlling the thread in a stitch forming mechanism. It is particularly adapted for use in connection with a cross thread laying mechanism. The operation of the thread controlling mechanism will therefore be described in detail as applied to the controlling of a cross thread. It is understood, however, that it may be used in connection with other elements of a stitch forming mechanism as, for example, for controlling the needle thread or a looper thread.

In the cross thread laying mechanism illustrated there is a cooperating thread guide and a loop forming finger which cooperate to form in the cross thread a loop which is laid so that it is entered by the two needles farthest disposed from the cross thread guide, while the other needle passes outside of the cross thread loop and secures the cross thread by laying its own needle thread over the shank of the cross thread loop.

This cross thread laying mechanism shown in the drawings forms the subject matter of my co-pending application, of which this is a division.

The invention herein is directed particularly as noted to the thread controlling mechanism. This thread controlling mechanism includes a cam shaped plate which is so disposed relative to stationary thread guides as to move into engagement with the thread passing through the guides and pull the same from the supply.

In connection with a cross thread laying mechanism the drawing up of the cross thread occurs at the time when the loop forming device moves into engagement with the cross thread. The controlling member for the thread is also provided with another cam shaped portion which engages the thread and places the same under tension. These devices operate in succession on the thread to take up and give up the same for each reciprocation of the controlling device. In connection with the cross thread laying mechanism the thread is placed under tension at the

time when the cross thread loop is completed and this insures that the strands of the cross thread loop will be taut and properly positioned relative to the needle. The above controls on the thread take place while the controlling mechanism is moving in one direction. While it is moving in the opposite direction then the cam plate again engages the thread passing between the guides and takes up the slack therein. In connection with a cross thread laying mechanism this occurs after the cross thread loop is formed and draws the cross thread loop comparatively taut in the stitch formation.

Referring more in detail to the drawings the invention will be described as applied to a cross thread laying mechanism but it is understood that it may be used in connection with other elements of the stitch forming mechanism. The thread controlling devices are applied to a sewing machine having the usual form of work support 1, overhanging arm 2 carrying a needle bar 3 provided with three needles 4, 5 and 6. Co-operating with these needles is the ordinary thread carrying looper. The needle bar is reciprocated by means of a needle lever 7 connected by a link 8 to the needle bar. The needle threads are indicated at n in the drawings. The needle threads on the upper face of the fabric are joined by a cross thread laid into loops. The cross thread is indicated at c . This cross thread passes from the supply through a suitable thread guide 9, and thence to an eye 10 in a member 11 secured to the overhanging arm. This member 11 is stationary. As clearly shown in Fig. 10 of the drawings the member 11 is provided with a U-shaped portion 12. Opposite the thread eye 10 is a second thread eye 13. The cross thread c passes first through the eye 10 and then the eye 13. This cross thread is then led to a movable cross thread guide 14. Said cross thread guide is provided with an eye 15 back from the end thereof and an eye 16 at the end thereof. The cross thread guide 14, as clearly shown in Figs. 4 and 5, is carried by an arm 17 which is L-shaped. This arm is pivotally mounted at 18 on a projecting arm 19 carried by a sleeve 20 which is mounted for free oscillation in a horizontal plane about the guide bar 21 which is associated with the presser bar 22. Mounted on the lower end of the presser bar 22 is a presser foot 23 and cooperating with this presser foot is a feeding mechanism which includes a feed dog 24.

The sleeve 20 is provided with a projecting arm 25. This projecting arm 25 carries a member 26 having a notched end 27. This notch faces outwardly and engages the cross thread running through the cross thread guide for forming a loop therein. The loop forming member 26, as noted, is carried by the arm 25 and when this arm is oscillated, the notched end of the loop forming member will move in a curved path about the axis of the guide bar 21 as a center. This curved path lies in front of the needles and extends from a point at one side of the needles to a point at the other side thereof, as clearly shown in Figs. 4 and 5. Mounted on the overhanging arm is a shaft 28. This shaft 28 is arranged with its axis vertical. The shaft carries an arm 29 and the arm 29 is pivoted at 30 to the elbow of the arm 17. This shaft 28 is oscillated by means of a link 31 which, in turn, is connected to an arm 32 carried by a horizontal cross shaft 33. This cross shaft 33 carries an arm 34 with which an eccentric strap 35 cooperates. The eccentric strap is actuated by an eccentric

on the main shaft beneath the work support.

In Fig. 5 of the drawings the thread guide is shown at the forward end of its stroke and the loop forming member about to engage the cross thread. When the arm 29 is oscillated said arm and the portion of the L-shaped member 17 between the pivotal point 30 and the pivotal point 18 will move toward alignment as clearly shown in Fig. 4. As these arms move nearer alignment it will force the arm 19 to the left and cause the sleeve 20 to turn in a clockwise direction about the center of the guide bar 21. This imparts a movement to the member 26 which carries the hook end thereof into engagement with the cross thread and forms in the cross thread a loop as clearly shown in Fig. 4. During this formation of the cross thread loop the cross thread guide is moving toward the rear of the machine. The end of the arm 17 will move rearwardly in a curved path about the center of the guide bar 21. The pivotal connection 30 between the arm 29 and the arm 17 will also move rearwardly in a curved path about the axis of the shaft 28 as a center. This combined rearward movement of the pivotal point 18 and the pivotal point 30 in the arm 17 brings about a substantially right line movement in the eye 16 at the end of the cross thread guide member which is parallel with the line of feed and at one side of the needles. This positions the thread eye 16 slightly in rear of a line passing through the three needles at right angles to the line of feed.

The strand of the cross thread loop running from the hook end of the oscillating member 26 to the eye 16 will be laid, therefore, in front of the two left hand needles as viewed in Fig. 4 and in rear of the right hand needle. The needles are preferably set with their points at different levels as shown in Fig. 1. This strand of the cross thread is laid against the front face of the middle needle and carried past the right hand needle beneath the point thereof which is set higher so that the middle needle will, in a measure, aid in the proper positioning of this strand of the cross thread loop. The other strand of the cross thread loop, of course, runs from the hook end of the oscillating member 26 to the previously formed stitches. As clearly shown in Fig. 7 the cross thread c is formed into a series of loops. The strand c^1 is the one running between the hook end of the oscillating member 26 and the eye 16 of the cross thread guide. The strand c^2 is the strand running from the hook end of the member 26 to the previous stitch.

The needle thread loops of the needle 4 are indicated at n^1 ; the needle thread loops of the needle 5 are indicated at n^2 ; the needle thread loops of the needle 6 are indicated at n^3 , and the fabric is indicated at F.

The operation of the cross thread laying mechanism described above will be obvious from the description given. The thread controlling devices for the cross thread include a cam plate 36 mounted on the needle bar and reciprocating between the thread guides 10 and 13. The cam plate is provided with a laterally projecting arm 37 which is secured to the needle bar by screws so that the arm is rigidly attached to the needle bar and moves up and down with the needle bar. This cam plate has an inclined face 38 which inclines downwardly and outwardly away from the needle bar to a rounded shoulder 39. It then inclines downwardly and inwardly toward the needle bar as indicated at 40, and terminates in a hook shaped cam portion 41. When the parts

are positioned as shown in Fig. 9 the needles are at the lower end of their stroke and the device for forming a loop in the cross thread is at the rear end of its stroke as shown in Fig. 5.

5 As the needle bar moves up the loop forming device engages the cross thread and begins the formation of the cross thread loop. The inclined face 38 of the cam plate engages the cross thread passing from the eye 10 to the eye 13 and deflects said cross thread, drawing thereon as indicated at the broken lines in Fig. 9. The cross thread at this time is taut and the cross thread is drawn from the supply. As the cam plate continues its upward movement the cross thread 10 passes over the rounded shoulder 39 and is released and gradually given up to the hook forming device as it moves on to form the cross thread 15 loop. When the needle bar reaches the upper end of its stroke the loop forming device has 20 reached the end of its forward stroke and is positioned as shown in Fig. 4. At this time the cross thread loop has been fully formed and properly positioned for the needles to pass the strands in the cross thread loop. The cam portion 25 41 of the plate 36 engages the cross thread and takes the slack out of the cross thread as the needle reaches the upper end of its stroke. At this time the cross thread is passed in front of the needle thread of the needle 6 (see Fig. 4). 30 This taut strand of the cross thread will hold the needle thread back so that when the needle 6 descends it will, with certainty, pass in front of the cross thread. It is true that slack is given to the cross thread as soon as the needle begins 35 its downward movement, but the needle point only moves a very slight distance above this cross thread, and therefore it will pass the cross thread before any appreciable slack is given thereto. On the down stroke of the needle bar the inclined 40 face 40 of the cam plate will engage the cross thread passing between the eyes 10 and 13 and will draw on the cross thread, thus taking up the slack in the cross thread formed by the loop forming device releasing the loop and this will 45 draw the cross thread loop substantially taut around the needles, and insures that in the completed stitch formation the cross thread loops will be substantially taut within the needle threads.

This cross thread controlling means is of particular advantage in connection with the cross thread laying mechanism described, wherein the cross thread loop is formed by a single loop forming device as the thread is drawn from the supply to enable the loop forming device to form its loop without undue strain upon the cross thread. It also insures that the cross thread will be taut at the time that this loop forming device and the cross thread guide cooperating therewith are positioning the strand of the loop 55 in a certain desired relation to the path of the needles, and it is of further advantage in the drawing of the cross thread loop taut when released by this loop forming device which has a relatively long movement in the forming of the 60 cross thread loop.

While I have described above my improved thread controlling mechanism as it is used in conjunction with a cross thread laying mechanism for controlling the cross thread in the formation of the cross thread loop, it will be understood that it may be used with other elements of a stitch forming mechanism such as a needle or a threaded looper.

In the operation of the thread controlling mechanism for each reciprocation of the mem-

ber carrying the thread engaging devices, said devices operate in succession to take up and give up thread. This is particularly useful in connection with a looper where it is essential to take up the thread as the looper moves forward to enter the needle thread loop and to give up thread as the looper moves on to the end of its stroke in the needle thread loop and to again take up thread on the first part of the retracting stroke of the looper and give up thread after the needle is well into the looper thread loop so as to permit the looper to move to the rear end of its stroke. This may be accomplished by my improved thread controlling mechanism wherein the reciprocating member is provided with independent devices for operating in succession to accomplish this taking up and giving up of the thread.

It is obvious that minor changes in the details of construction may be made without departing from the spirit of the invention as set forth in the appended claims.

Having fully described my invention, what I claim as new and desire to secure by Letters Patent, is:—

1. The combination of a needle bar, a plurality of needles carried thereby, a cross thread laying mechanism including devices for forming a loop in a cross thread, and controlling devices for the cross thread including means for intermittently engaging the cross thread for drawing the same from the supply on the upward movement of the needle bar.

2. The combination of a needle bar, a plurality of needles carried thereby, a cross thread laying mechanism including devices for forming a loop in a cross thread, and controlling devices for the cross thread including means separate from the loop forming devices for engaging the cross thread for taking up the slack therein and drawing said cross thread taut when the loop forming devices complete the formation of the loop in the cross thread, so that said cross thread will properly position the needle thread of the right-hand needle and insure that said thread passes in front of the cross thread on its down stroke.

3. The combination of a needle bar, a plurality of needles carried thereby, a cross thread laying mechanism including devices for forming a loop in a cross thread, and controlling devices for the cross thread including means for engaging the cross thread and drawing the same from the supply on the upward movement of the needle bar and for taking up the slack in the cross thread as the loop forming device reaches the forward end of its stroke and for taking up the slack in the cross thread loop and for drawing the formed loop taut about the needle thread as said cross thread loop is released by the loop forming device.

4. The combination of a needle bar, a plurality of needles carried thereby, a cross thread laying mechanism therefor, devices for guiding the cross thread to said cross thread laying devices, and controlling means for said cross thread, said controlling means including a member reciprocating with the needle bar and operating to take up the cross thread, then give slack to the cross thread, and finally to again take up the cross thread during each cycle of operation of the cross thread laying mechanism.

5. The combination of a needle bar, a plurality of needles carried thereby, a cross thread laying mechanism therefor including a cross thread guide movable in a line at one side of the needles and a cross thread loop forming device oscillating

in a curved path in front of the needles, a controlling cam plate for the cross thread, stationary guides at each side thereof for directing the cross thread, said plate being shaped so as to engage the cross thread and draw thread from the supply on the upward movement of the needle bar.

6. The combination of a needle bar, a plurality of needles carried thereby, a cross thread laying mechanism therefor including a cross thread guide movable in a line at one side of the needles and a cross thread loop forming device oscillating in a curved path in front of the needles, a controlling cam plate for the cross thread, stationary guides at each side thereof for directing the cross thread, said plate being shaped so as to engage the cross thread and draw thread from the supply on the upward movement of the needle bar, said cam plate also engaging the cross thread for taking up the cross thread when the loop forming device reaches the forward end of its stroke and holding the cross thread taut as the needles are passing the cross thread and certain of said needles are entering into the cross thread loop.

7. The combination of a needle bar, a plurality of needles carried thereby, a cross thread laying mechanism therefor including a cross thread guide movable in a line at one side of the needles and a cross thread loop forming device oscillating in a curved path in front of the needles, a controlling cam plate for the cross thread, stationary guides at each side thereof for directing the cross thread, said plate being shaped so as to engage the cross thread and draw thread from the supply on the upward movement of the needle bar, said cam plate being also shaped so as to engage the cross thread on the downward movement of the needle bar for taking up the

slack in the cross thread and drawing the formed cross thread loop taut about the needle threads as it is released by the loop forming device.

8. The combination of a needle bar, a plurality of needles carried thereby, a cross thread laying mechanism therefor including a cross thread guide movable in a line at one side of the needles and a cross thread loop forming device oscillating in a curved path in front of the needles, a controlling cam plate for the cross thread, stationary guides at each side thereof for directing the cross thread, said plate being shaped so as to engage the cross thread and draw thread from the supply on the upward movement of the needle bar, said cam plate also engaging the cross thread for taking up the cross thread when the loop forming device reaches the forward end of its stroke and holding the cross thread taut as the needles are passing the cross thread and certain of said needles are entering into the cross thread loop, said cam plate also engaging said cross thread on the downward movement of the needle bar for taking up the slack in the cross thread and drawing said formed loop taut about the needle threads as it is released by the loop forming device.

9. In a thread controlling mechanism for sewing machines, the combination of spaced thread guides, a reciprocating member, a cam plate carried by said reciprocating member and adapted to move between said thread guides, said cam plate being provided with independent devices operating in succession, one of which takes up and gives up thread for each up and down stroke of the needle, and the other of which takes up thread on the up stroke of the needle and gives up thread on the down stroke thereof.
